UNITED STATES PATENT OFFICE.

WILLIAM S. GRAHAM, OF CANTON, ILLINOIS, ASSIGNOR TO PARLIN & ORENDOFF COMPANY, OF CANTON, ILLINOIS, A CORPORATION OF ILLINOIS.

GANG-FLOW.

1,295,479.

Specification of Letters Patent. Patented Feb. 25, 1919.

Application filed April 10, 1914. Serial No. 830,905.

To all whom it may concern:

Be it known that I, WILLIAM S. GRAHAM, a citizen of the United States, residing at Canton, in the county of Fulton, State of Illinois, have invented certain new and useful Improvements in Gang-Plows, of which the following is a specification, reference being had to the accompanying drawings.

This invention relates to gang plows and particularly to that class of gang plows adapted to be drawn across a field by a traction engine. It is one of the objects of my invention to provide means involving the use of only a single shaft adapted to be actuated at the will of the operator from one of the supporting wheels of the plow for raising and lowering the plows. It is another object of my invention to provide a construction involving a shaft for raising and lowering the plows such that a rotation of the shaft when the plows are in lowered position serves to raise the plows and a rotation of the shaft when the plows are in raised position serves to release the plows from raised position. It is another object of my invention to provide means for raising and lowering the plows involving the use of a single operating cord for throwing the raising means into operation, such that a pull upon the cord when the plows are in raised position is effective to bring about the release of the plows from raised position and a pull upon the same cord when the plows are in lowered position is effective to bring about the raising of the plows. It is another object of my invention to provide a construction involving the use of links for drawing the plows to elevated position, the forward ends of said links being adapted to be moved in the plow lifting operation into a past-center locking position, means being provided for holding the rear ends of the links in a normal predetermined position while the plows are in raised position regardless of the angular position of the plow beams relative to the plow frame. It is another object of my invention to provide means in connection with such a link construction for preventing the undue sagging of the rear ends of the links when the plows are in lowered position. It is another object of my invention to improve devices of this type in sundry details hereinafter pointed out. The preferred means by which I have accomplished these objects are illus-

trated in the drawings and are hereinafter specifically described.

In the drawings:

Figure 1 is a top or plan view of a gang plow embodying my improvements, only two of the several plows being shown;

Fig. 2 is a side view of the plow shown in Fig. 1, but with only one of the plows illustrated and with one of the supporting wheels removed;

Fig. 3 is an enlarged detail of one of the power elevating devices in position ready for raising a plow upon the actuation of the power shaft;

Fig. 4 is a similar view, but showing the position of the parts after the plow has been raised with the link in its past-center locking position for holding the plow against descending;

Fig. 5 is a similar view but showing the position of the parts when the power shaft has been given a partial rotation from the position shown in Fig. 4, with the parts in position for the plow to fall freely to the ground.

Fig. 6 is a top or plan view of the parts as shown in Fig. 4;

Fig. 7 is an enlarged diagrammatic view showing the relative positions of the lifting and releasing arms upon the power shaft;

Fig. 8 is a view of the clutch mechanism by which the power shaft is adapted to be operatively connected with the source of power for lifting purposes, being substantially a section taken on line 8-8 of Fig. 1; and

Fig. 9 is a top or plan view of the parts shown in Fig. 8.

Referring to the several figures of the drawings, in which corresponding parts are indicated by the same reference characters,

20-21 indicate the side bars of the frame of my plow converging at their forward ends and having mounted thereon a caster wheel 22. The bars 20-21 are connected at their rear ends to the diagonally-extending rear frame-bar 23 to which the plow beams are adapted to be connected. Journaled upon an axle 24 carried by the bars 20 and 23 near their rear ends is a ground wheel 25 provided with studs 26 on its periphery by which the wheel is enabled to properly grip the ground for power purposes. Near the front end of the diagonal bar 23 in rear thereof there is provided a supporting wheel 110

27. Diagonally-positioned brace-bars 28—29 extend from the side bars 20—21 respectively, to the diagonal bar 23.
- 30—31 indicate brackets mounted upon the diagonal bar 23 in any suitable manner, on each of which brackets there are pivotally mounted upon a horizontal axis bars 32—33 comprising a plow beam, upon which plow beams plows 34—35 are mounted in any suitable manner by means of standards 36. Each of the plow beams has pivotally mounted upon it a swinging arm 37, upon the lower end of which there is journaled a gage wheel 38 adjustable relative to the plow beam through the medium of a bell crank lever 39 and a link 39^a in the manner shown and described in Letters Patent to me No. 1,084,081, of January 13, 1914. A lever 40 is provided in connection with each of said bell-crank levers as described in said patent, adapted to be locked at any desired point upon the circular rack-bar 41 and adapted through the medium of a stop 39^b on the said bell crank lever to limit the movement of the bell-crank lever in counter-clockwise direction in Fig. 2. As will be readily understood the lever 40 is also adapted to be swung in clockwise direction in said figure for turning the bell crank lever in the same direction for raising the beam and the plow carried thereby upon the gage wheel.
- 42—43 indicate the transverse bars of an auxiliary frame secured upon the main plow frame by means of angle irons 44 or in any other suitable manner. The cross-bars 42—43 of the auxiliary frame are joined by a plurality of bars 45, one of such bars being provided for each of the plow beams.
- 46 indicates a transverse power shaft revolvably mounted in the auxiliary frame comprising the bars 42, 43 and 45. As best shown in Figs. 8 and 9, 47 indicates a clutch member revolvably mounted upon the shaft 46 at one end thereof, provided upon its outer periphery with a sprocket-gear 48. Said sprocket-gear 48 is connected by a sprocket-chain 49 with a sprocket-gear 50 revolvable with the ground wheel 25. The clutch member 47 is thus maintained during the forward movement of the plow constantly in rotation in clockwise direction in said Fig. 8.
- The means for locking the shaft 46 with the clutch member 47 so as to rotate said shaft comprise a bracket 51 keyed or otherwise fixed upon the shaft 46 adjacent to the clutch member. Pivotally mounted upon the bracket 51 upon a pin 52 carried thereby is an arm 53 provided with a roller 54 adapted to be brought into operative engagement with any one of the rounded notches or grooves 55 formed on the inner periphery of the drum-like clutch member 47. A spring 56 serves to connect the bracket 51 with the arm 53 tending to hold the arm 53 turned

in clockwise direction upon the pivot pin 52 to bring the roller 54 into operative engagement with one of the notches 55. The bracket 51 is provided at its outer end with a notch 57 adapted to receive a roller 58 mounted upon the lower end of a bar 59 pivotally mounted by means of a pivot pin 60 upon one of the cross-bars 45 of the auxiliary frame, said roller 58 being of such a width as to engage also the adjacent pivotally-mounted arm 53. Said bar 59 is provided with an opening in its upper end by which a cord or cable 60' is secured to said arm, said cord being provided for the purpose of pulling the upper end of said arm forward against the action of a spring 61 secured thereto. As clearly shown in Fig. 8, the roller 58 carried by the lower end of the arm 59 when in normal position in the notch 57 in the outer end of the bracket 51 serves to hold the roller 54 carried by the arm 53 displaced to the right in said figure out of operative engagement with the clutch member 47.

As will be readily understood, when it is desired to give the shaft 46 a rotation in clockwise direction in Fig. 8, the arm or lever 59 is given a stroke in clockwise direction in said figure by a forward pull upon the cord 60' or in any other suitable manner, withdrawing the roller 58 from the notch 57. The arm 53 is then turned upon the pin 52 by the spring 56, bringing the roller 54 into operative engagement with one of the notches or grooves 55, causing the shaft 46 to turn in clockwise direction in said figure with the constantly-rotating clutch member 47. As soon as the bracket 51 has been turned sufficiently to clear the roller 58, the lever 59 may be released, whereupon the spring 61 serves to return such lever 59 to the position shown in Fig. 8. When the bracket 51 has substantially completed a single rotation the front edge of the bracket is brought into contact with the roller 58, causing the displacement of said roller to the left in Fig. 8 until the roller can again drop into normal position in the notch 57 of said bracket, displacing the arm 53 and roller 54 as above described, thus stopping the rotation of the shaft 46.

Adjacent to each of the bars 45 of the auxiliary frame there is revolvably mounted upon the shaft 46 an arm 62, said arm being held in position on said shaft by the hub 63 of the lifting bracket 64 fixed upon said shaft adjacent to the hub 65 of said arm. Pivotally mounted upon the outer end of said arm 62 is a link 66 to which, near its rear end, a second link 67 is pivotally connected. As best shown in Figs. 1 and 2, the rear end of each of the links 67 passes freely through a perforated lug 68 carried by one of the bell crank levers 39. Each of said links 67 has adjustably mounted upon it a

stop device 68', in the construction shown said stop device being in the form of a nut secured thereon by means of screw-threads. As best shown in Figs. 3 and 6, 69 indicates 5 a pin or stud extending laterally from the link 66 rearwardly of the pivotal connection between said links 66—67, said stud 69 being adapted to rest upon the link 67 so as to keep said links 66—67 substantially in 10 alinement with each other and to prevent their sagging downward at their pivotal connection.

Each of the brackets 64 comprises two arms 70—71, the arm 71 being slightly 15 longer than the arm 70 and being provided with a notch 72 in its outer end. Upon each of the arms 62 is pivotally mounted a pawl 73 in alinement with the bracket 64 adjacent to said arm. Upon the pivot pin 20 74 of each of said pawls there is mounted a light coiled spring 75 which bears upon the pawl, tending to hold the pawl frictionally against swinging relative to the arm 62. Upon a rotation of the shaft 46 in clockwise direction in Fig. 3, the arm 71 is brought 25 into engagement with the end of the pawl 73, causing the arm 62 to turn in clockwise direction with said shaft, swinging the bell crank lever 39 in clockwise direction in Fig. 30 2 through the medium of the links 66—67 and causing the plow 35 to rise out of the ground upon the gage wheel 38. Soon after the pivotal connection between the link 66 and the arm 62 passes below the center of 35 the shaft 46, the end of the pawl 73 in advance in its movement with the arm 62 is brought in contact with a stud or roller 76 carried by the bar 45, causing the pawl to turn in clockwise direction relative to the 40 arm 62, freeing the end of said pawl from the notch 72 of the lifting arm 71. The arm 62 then comes to rest upon the stud or roller 76 with the end of the link 66 in a past-center locking position, as will be readily 45 understood, serving to maintain the plow in elevated position. When the shaft 46 has completed a single revolution, its rotation is stopped as above described, with the parts in the condition shown in Fig. 4. With 50 the plow held in raised position, as illustrated in Fig. 4, the rear end of the link 66 is supported by a standard 77 mounted upon the transverse bar 42 of the auxiliary frame. In this position the stud 69 is at some little 55 distance from the link 67 so that at whatever angle the link 67 extends rearwardly from its pivotal connection with the link 66 the link 66 itself is held always in the same position relative to the shaft 46.

60 Whenever it is desired to lower the plows, the shaft 46 is again set in rotation, bringing the arms 70 of the brackets 64 into contact with studs or rollers 78 carried by the link 66, serving to raise the forward ends of 65 said links out of their past-center locking

position whereby the plows are permitted to drop by gravity into working position. The rotation of the arm 62 in counterclockwise direction is limited by a pin 79 carried by the bar 45 of the auxiliary frame. As the 70 arm 62 approaches its rearmost position, as shown in Fig. 3, the pawl 73 is brought in contact with a stud or roller 80 carried by the frame-bar 45, serving to turn the pawl 75 75 into position to be engaged by the arm 71 of the bracket 64 upon the next succeeding rotation of the shaft 46. By reason of the shorter length of the arm 70, such arm 70 is adapted to be turned past the pawl 73 80 without operatively engaging it.

From the above description it will be seen that a rotation of the shaft 46 with the plow in raised position serves to release the plow from raised position by raising the link 66 85 out of its past-center locking position; and that a rotation of the shaft 46 with the plows in their lowered position serves to raise said plows. That is to say, each alternate rotation of the shaft 46 serves normally to raise the plows, and each other alternate rotation of said shaft is effective to bring about the lowering of the plows.

As will be readily understood, each of the 90 plows is provided with raising means of the type above described, comprising an arm 62, a bracket 64, links 66 and 67 and pawl 73, whereby said plows are raised and lowered by independently-acting mechanisms actuated by the shaft 46 and its operating 95 means. As is best shown in Fig. 7, the brackets 64 are preferably staggered upon the shaft 46 relative to each other whereby the several plows are raised successively, as 100 is well understood in the art.

While I have shown the cable 60' in the 105 form of a flexible cord, it will be understood that I do not wish to limit myself to that particular construction except as hereinafter specifically claimed.

With the operating means by which the 110 rotation of the shaft 46 is effectively transmitted to the several plows for raising purposes in operative position with the pawls 73 turned upon their pivot pins 74 so as to 115 be engaged by the arms 71 of the bracket 64, the operation of the machine will be normal, as above described. It will be readily understood, however, that if such operating parts should not be moved completely into 120 operative position whereby any of the arms 71 when the plows are in lowered position might be moved past the corresponding pawl 73 without engaging it, the rotation of the shaft 46 would then fail to have any effect 125 upon the plow normally adapted to be raised through the use of such arm and pawl. While it is important that some expedient be employed for insuring that the operating parts including the pawls 73 shall be in oper- 130

ative position when desired, I wish to have it understood that I do not limit myself to the particular means shown nor to any automatically-acting means for accomplishing this result, except as hereinafter specifically claimed.

While my raising and lowering means is designed normally for raising all of the plows in order and for thereafter lowering all of the plows in order, it will be understood that the mechanism as shown is adapted to operate effectively whether all the plows are being raised together in order or not. For example, if when all the plows are standing in raised position the operator should manually raise one of the links 66 so as to permit one of the plows to fall to the ground, then upon the next complete rotation of the shaft 46 the plows in raised position would be lowered and the plow in lowered position would be raised.

By the use of the standards 77, regardless of different angles at which the plow beams stand on account of the unevenness of the ground, the links 66 are all maintained at a uniform angle when the plows are in raised position so that the arms 70 are brought into effective operation to raise such links at precisely the proper intervals for dropping the plows successively as desired.

What I claim as my invention and desire to secure by Letters Patent, is—

1. In a gang plow, the combination of a frame, a plow operatively connected with said frame and adapted to be raised and lowered relative thereto, a shaft, a link operatively connected with said plow extending adjacent to said shaft, means carried around by a rotation of said shaft adapted to exert a pull upon said link for raising said plow and for moving the forward end of said link into a past-center locking position, and a standard mounted on the frame in alignment with said link upon which standard the rear end of the link rests when the plow is in raised position, the link being thus kept constantly in normal position relative to the releasing

means while the plow is in raised position whereby the releasing may be accurately timed.

2. In a gang plow, the combination of a frame, a plow operatively connected with said frame and adapted to be raised and lowered relative thereto, a rigid link operatively connected with said plow at its rear end whereby a forward pull upon said link serves to raise said plow, a second rigid link pivotally connected to said first-named link, means for exerting a forward pull upon said second link for raising said plow, and means for preventing said links from sagging at their pivotal connection.

3. In a gang plow, the combination of a frame, a plow operatively connected with said frame and adapted to be raised and lowered relative thereto, a rigid link operatively connected with said plow at its rear end whereby a forward pull upon said link serves to raise said plow, a second rigid link pivotally connected to said first-named link, and means for exerting a forward pull upon said second link for raising said plow, said links being adapted to swing upward freely at their pivotal connection but being limited in their downward swinging relative to each other.

4. In a gang plow, the combination of a frame, a plow operatively connected with said frame and adapted to be raised and lowered relative thereto, a rigid link operatively connected with said plow at its rear end whereby a forward pull upon said link serves to raise said plow, a second rigid link pivotally connected to said first-named link, means for exerting a forward pull upon said second link for raising said plow, and means carried by one of said links adapted to engage the other link for limiting the swinging of said other link in an upward direction relative to said one link.

WILLIAM S. GRAHAM.
